MOTOR COOLING AND VEHICLE BODY
HEATING SYSTEM

Samuel Willis Rushmore, Plainfield, N. J.

Application March 27, 1942, Serial No. 436,395

3 Claims. (Cl. 123—174)

This invention relates to improvements in cooling systems for internal combustion engines and associated vehicle body heating means adapted to present important advantages and an improved mode of operation conducive to better cold weather operation of the motor.

The present improvements are desirably incorporated with an internal combustion engine of the type adapted to be water cooled with a boiling and condensing cycle of the cooling liquid as illustrated in my prior Patent No. 1,851,407 of March 29, 1932. As therein shown, the water and steam from the top of the water jacket of the motor are discharged into the base of the radiator and the steam condensed in passing upwardly therethrough to the top tank of the radiator. From the latter the water is fed, under the action of a pump, to the water jacket of the engine to complete the cycle in the manner as described. Incident to this perfected type of cooling system certain important advantages are obtained including reduced piston friction, better vaporization and combustion of the fuel gases, elimination of crank case dilution and prevention of rusting thereby increasing the life of the engine.

In accordance with the present invention there is associated therewith provision for maintaining a pressure in the engine jacket materially higher than the pressure in the cooling radiator. This, moreover, is with advantage combined with a vapor heating system for the vehicle body and with the employment of a special form of pressure valve having a vacuum relief or supplementary valve provides for a desirable added degree of protection to the engine against freezing peculiarly valuable to the referred to type of motor cooling wherein under certain conditions of cooling off of the motor on shutting down there results an objectionable separation of the water and alcohol between the jacket and the radiator thereby increasing the hazard of freezing. As illustrative, with the use of alcohol in the cooling liquid upon starting up of the motor the first vaporization will be chiefly that of the alcohol, which boils at about 175 degrees F., thereby transferring a substantial part of the alcohol content to the radiator and its tank.

With the present improvements the vacuum relief valve permits return flow of the alcohol fluid from the radiator upon cooling within the jacket with a desirable increased flow under the influence of like cooling and condensation in the vehicle body heating system as will be understood. In addition, the relatively high pres-

sure maintained in the engine jacket, desirable for proper circulation of the steam for body heating, is materially beneficial in raising the normal operating temperature of the motor. This accordingly avoids the objectionable factor of undesirable lowering of the jacket temperature incident to the use of alcohol as customarily occurs and which operates against good motor performance.

10 The foregoing and other valuable features and advantages of the present invention will be more fully understood by reference to the accompanying drawing wherein like reference characters are applied to the corresponding parts in the several views.

In the drawing:

Fig. 1 is a view in side elevation, partly in section showing the present invention incorporated with an internal combustion engine and 20 radiator therefor.

Fig. 2 is a partial, detailed vertical sectional view showing the pressure valve with relief.

Fig. 3 is a horizontal, sectional view of the 25 relief and pressure valve taken on line 3—3 of Fig. 2.

In the approved embodiment of the invention as here shown, the motor is conventionally shown as including the usual crank case 1 and cylinder block 2, the upper parts of which are 30 enclosed by water jacket 3. The water cooling system is conventionally indicated as including the radiator 4, located as usual on the same level with the motor and directly in front of it, so that the lower part of the radiator is below 35 the level of the water jacket of the motor. The circulation of the water from the top tank 15 of the radiator is through a pipe 5 to pump 6, the latter being preferably driven from the engine at directly proportional speed. The pump is indicated as being a gear pump but this is merely to 40 illustrate that the pump is adapted to receive the water and force it into the water jacket against friction and any back pressure that may be caused by steaming and as in the present invention pressure within the jacket. This pump 45 discharges through a pipe 7, preferably into the top of the water jacket 3, whence the path of flow is through a riser outlet 8 and downwardly extending return pipe 9 which discharges into the 50 bottom tank of the radiator.

The pipe 7 contains a check valve 10 to insure against back flow of water or steam such as might otherwise occur under operating conditions when the engine and pump are stopped.

55 This valve is located a substantial distance above

the level of the pump 6 so that the output side of the pump will always be submerged in a substantial amount of water.

In general, the bottom of the upper tank 15 is substantially below the desired initial level of water in the engine jacket 3, when the latter is full; the intake level 5a is substantially above said level and the height of the tank above the intake is such as to provide a substantial storage space into which a substantial part of the total water of the system may rise above the intake 5a under extreme conditions of high temperature, hard boiling. The referred to features conform to the disclosure of the patent referred to and possesses special operating advantages as referred to in addition to other advantages including reduction in the time of the warming up period of the motor. In combination therewith, as shown, means are provided for the heating of the vehicle body by steam from the water jacket which is conventionally indicated by supply pipe 21 from the jacket, heating coil 22 for heat radiation within the body and return pipe 23 communicating with the radiator lower tank 12.

In accordance with the present improvements, the structure is modified to include a pressure valve 25 desirably located as shown at the discharge port of the engine jacket as part of the riser 8 connecting with the radiator return pipe 9. This valve comprises a casing 26 secured to the upper wall of the cylinder jacket by screws 27. The casing is formed with a nipple 28 communicating with the riser pipe 8 attached thereto. Within the casing there is provided a sleeve valve member 30 having a bottom valve disc portion 31 formed to close the discharge opening or port 33 in the jacket wall. The valve is spring pressed by compression spring 35 for normal closing of the valve against the jacket wall seat and the disc portion is formed with the marginal openings 36—36 open to the interior of the valve sleeve outward of the port opening 33. The valve disc portion is further provided with inwardly positioned openings 38 normally closed by a spring pressed valve 40 slidably fitted to a screw stud 42 and pressed against the valve disc 31 by compression spring 43 interposed between the valve 40 and a bearing washer 45 as shown. The valve 40 is thus adapted to open responsive to pressure acting reversely of the pressures operative to open the sleeve valve 31 and is moreover designed to open under relatively low pressures and as will be noted is held closed by pressure from within the jacket.

In the resulting operation, the heat of the motor will build up a steam pressure within the jacket determined by the sleeve valve, which may desirably be about ten pounds pressure, thus providing the required pressure for circulating the steam through the body heating connections with the excess steam passing to the radiator 4 from pipe 9. Upon shutting down and cooling of the motor a vacuum is built up within the jacket from condensation therein and within the body heating connections at which time the lighter pressure yielding valve 40 permits return of fluid from the radiator, normally open to atmospheric pressure, thereby insuring alcoholic content fluid protection within the jacket.

This constant and relatively high pressure within the jacket is particularly valuable in maintaining a higher temperature within the jacket

under normal running thus contributing to improved motor performance in cold weather operation. There is further a material reduction of water and steam sent over to the surge tank 12 and reduction of violent boiling under extreme operation and reduced likelihood of formation of steam pockets in the circulation.

The upper tank 15 is provided with the usual filler closure 18 and water overflow pipe 17. A cock 20 is provided at the desired normal or cold water level in the system, which is ordinarily the top of the water jacket cavity of the engine. This cock may be open when the system is filled with water or fluid cooling medium so that the operator may observe when the desired water level is reached and may then be closed.

While the improved features and mode of operation are particularly effective and desirable in combination with the body heating circulation, it will be understood that material advantages are present without such body heating particularly as relating to increase in the temperature under normal operation resulting from the higher jacket pressures which may be as high as fifty pounds pressure with desirable results of improved motor operation.

Having described my invention, I claim:

1. An internal combustion engine having a boiling and condensing cycle cooling system including an engine water jacket and a radiator providing normally separate, non-interflow, fluid reservoirs, means for circulating a cooling medium from the jacket through the radiator and pressure responsive valve means associated with the circulating means to be operative on motor operation to maintain a pressure in the engine jacket materially higher than the pressure in the radiator and adapted to permit return flow from the radiator to the jacket responsive to vacuum in the jacket incident to cooling of the engine.

2. An internal combustion engine having a boiling and condensing cycle cooling system including an engine water jacket and a radiator providing normally separate, non-interflow, fluid reservoirs, means for circulating a cooling medium from the jacket through the radiator and valve means in the circulating means consisting of a pressure responsive valve operative to maintain a pressure in the engine jacket materially higher than the pressure in the radiator and provided with a reversely acting vacuum relief valve to permit return flow from the radiator to the jacket responsive to vacuum in the jacket incident to cooling.

3. An internal combustion engine having a boiling and condensing cycle cooling system including an engine water jacket and a radiator providing normally separate, non-interflow, fluid reservoirs, means for circulating a cooling medium from the jacket through the radiator including a pipe connection from the jacket to the radiator and valve means in series with said pipe connection consisting of a spring pressed sleeve valve operative to maintain a pressure in the jacket higher than within the radiator and said valve being provided with a supplementary, reversely acting spring valve operative to permit return flow from the radiator to the jacket responsive to vacuum in the jacket incident to cooling.

SAMUEL W. RUSHMORE.
